Primary Examiner — Samantha Wood*Assistant Examiner* — Vanessa Martinez(74) *Attorney, Agent, or Firm* — Vladimir Postnikov(57) **CLAIM**

The ornamental design for a vehicle light, as shown and described.

DESCRIPTION

FIG. 1 is a front elevation view of a vehicle light showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof;

FIG. 8 is another perspective view thereof;

FIG. 9 is an enlarged view of portion 9 shown in FIG. 1;

FIG. 10 is an enlarged view of portion 10 shown in FIG. 1;

FIG. 11 is an enlarged view of portion 11 shown in FIG. 5;

FIG. 12 is an enlarged view of portion 12 shown in FIG. 6; and,

FIG. 13 is an enlarged view of portion 13 shown in FIG. 7. The equal length broken lines depict portions of the vehicle light that form no part of the claimed design.

The dash-dot lines in FIGS. 1, 5, 6, 7, 9, 10, 11, 12, and 13 illustrate the enlarged view indicators and form no part of the claimed design.

1 Claim, 13 Drawing Sheets
